Hill.

UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

Application filed June 14, 1924. Serial No. 719,923.

This invention aims to provide an improved separable fastener, preferably, though not exclusively, for use in securing automobile curtains to the body of the car.

5 In the drawings, which illustrate a preferred embodiment of my invention:—

Figure 1 is a front elevation of a preferred form of fastener;

10 Fig. 2 is a rear elevation of a preferred form of stud, herein shown as attached to an automobile curtain;

Fig. 3 is a section, partly in elevation, on the line 3—3 of Fig. 1, showing the stud partly entered within the socket;

15 Fig. 4 is a section similar to Fig. 3 showing the stud locked to the socket;

Fig. 5 is a front elevation of a preferred form of socket; and

20 Fig. 6 is a side elevation of the preferred form of socket.

Referring to the drawings and to the preferred form of fastener selected for illustrative purposes, I have shown a stud including a contractile and expansible head 1, herein shown as relatively short and integral with a back plate 2. The stud may be secured to a curtain 3 by prongs 4 struck up from the periphery of the back plate 2 and these prongs pass through the curtain and 25 are deflected by an anvil part against an inwardly bent flanged portion 5, both of which are integral with a front plate 6 located on the opposite side of the curtain. The front plate also presents a concaved 30 portion 7 surrounding an aperture 8, the purposes of which are more fully hereinafter described.

The preferred form of socket, as illustrated in the drawings, is of the flush type and presents a preferably hexagonal body portion 9 countersunk into the body 10 of the car and embracing the hexagonal head 11 of a screw 12 which holds the socket in place on the body of the car. A preferred form 45 of means for holding the head of the screw in a fixed relation to the body 9 of the socket comprises indented portions 13, of which there is one pressed from each flat side of the body of the socket.

50 The head 11 of the screw 12 is seated against these indented portions and held thereagainst by rolling a portion of the body 9 of the socket over the edge of the head 11

and clenching it against the face thereof.

Thus the head 11 of the screw is held in a 55 fixed relation to the socket, as best illustrated in Figs. 3 and 4.

The socket also presents a front face 14, which is secured to the hexagonal flange integral with the outer end of the body, thus 60 presenting a flange which overlies the body portion 9 sufficiently to conceal the hole in the body of the car into which the body portion of the socket fits when secured to the body of the car.

65 The front face 14 also presents a stud-receiving aperture 15 for reception of the head 1 of the stud which may be locked therein against contraction by a locking shoulder 16 located between a press-button 17 and a sealing disc 18, all of which are normally urged forward into aperture-closing position by a spring 19 interposed between the head 11 of the attaching screw and the sealing disc 18. The press-button 17 is 70 preferably, as illustrated, pressed from the sealing disc and the locking shoulder is preferably located adjacent the front face of the sealing disc and engages the inside of the contractile and expansible head, when engaged in the stud-receiving aperture, to prevent contraction thereof and separation from the socket by a strain on the curtain not intended to separate the stud from the socket. When the stud and socket are locked together the press-button passes through the head of the stud and the aperture 8 in the 75 front plate 6.

80 The concaved portion surrounding the aperture 8 is of importance inasmuch as it provides a recess into which the operator of the fastener may insert a finger to press the press-button when unlocking the fastener. Thus the necessary length of the press-button beyond the front face of the socket 85 is greatly reduced so that the press-button will not be an objectionable projection upon which clothing may catch.

86 The stud may be secured to the socket by merely forcing the head 1 of the stud into 100 the stud-receiving aperture 15. The head then contracts and the reversely bent portions 20 of the head engage the locking shoulder 16 and forces the press-button, locking shoulder and sealing disc inwardly 105 against the pressure of the spring 19. After

the stud is fully engaged with the aperture, the head expands and the locking shoulder is forced by the spring 19 into the head of the stud where it engages the reversely bent portions 20 and locks the stud with the socket.

Separation of the fastener is effected by grasping the lower edge of the curtain 3 and exerting a slight outward pull thereon at the same time pressing inwardly on the press-button 17 to disengage the locking shoulder from the inner periphery of the reversely bent portions of the stud, thereby to permit contraction of the head and withdrawal thereof from the socket.

The type of fastener herein described and illustrated is very much simplified over other known types of fasteners which are locked on all sides when secured to each other. In my preferred form of stud, there is no mechanism to get out of order, and in the preferred form of socket there is little or no mechanism to get out of order. The number of parts in the stud has been reduced to a minimum without any increase in the number of parts in the socket, thus reducing the cost of such types of fasteners without affecting the durability thereof.

While I have shown and described a preferred form of one embodiment of my invention, it will be understood that changes involving alteration, omission, substitution and reversal of parts, and even changes in the mode of operation, may be made without departing from the scope of my invention, which is best defined in the following claims.

Claims:

1. A separable fastener comprising, in combination, a socket presenting a stud-receiving aperture, a stud having a head contractible and expansible for engagement with said aperture, locking means and press-button means located in said socket and adapted to engage and lock said stud with said socket, said press-button means manually operable through an aperture extending through said stud and shift said locking means to permit contraction and withdrawal of said stud from said socket.

2. A separable fastener comprising, in combination, a socket presenting a stud-receiving aperture, a spring-pressed locking member carried by said socket adjacent said aperture, a press-button integral with and extending from said locking member and a stud having a contractible and expansible head for engagement with said aperture, said locking member adapted to lock said head in said aperture and said press-button presented at the opposite side of said stud from the head thereof for manual operation of the locking member to permit separation of the fastener.

3. A separable fastener comprising, in combination, a stud having a contractible

and expansible head secured to a flexible fabric, a front plate presenting a concaved portion surrounding an aperture, a cooperating socket presenting a stud-receiving aperture and a spring-pressed one-piece locking member and press-button, said locking member adapted to engage and lock said head with said socket and said press-button presented in said aperture in said front plate, said concaved portion providing a recess into which may be inserted a finger of the operator to press said press-button thereby to displace said locking member for separation of said stud from said socket.

4. A separable fastener comprising, in combination, a stud having a contractible and expansible head, a cooperating socket presenting a stud-receiving aperture, a locking part in said socket for locking said stud with said socket and a press button assembled with said locking part and protruding from said aperture through said stud to be exposed at the front face of the stud member when the stud and socket are engaged, thereby to permit direct operation thereof by the operator of the fastener.

5. A separable fastener comprising, in combination, a socket including a casing presenting a stud-receiving aperture, a one-piece locking and unlocking member normally urged toward said aperture by a spring, said one-piece member forming part of the fastening assembly and a stud presenting a relatively short contractible and expansible socket-engaging member for engagement with said aperture, said socket-engaging member adapted to receive said unlocking portion while excluding said locking portion when engaging said aperture, while adapted to expand and receive said locking portion when engaged with said aperture thereby locking said stud and socket against separation by a strain at any side thereof.

6. A socket for a separable fastener including a casing having a front face presenting a stud-receiving aperture, a resiliently pressed locking part adjacent said aperture and a manually operable press-button adapted to be operated by direct contact with a finger of the operator therewith, said press button extending beyond the front face of said casing, said locking part and press-button part being assembled with said casing.

7. A socket for a separable fastener including a casing presenting at one end thereof means for securing said casing to a support and at the other end thereof a stud-receiving aperture, an axially shiftable locking part adjacent to said aperture, and a spring-pressed press-button for passage through a stud when engaged with said socket to permit manual shifting of said locking part, said locking part and press-

button forming part of the socket assembly.

8. A socket for a separable fastener including a casing presenting a stud-receiving aperture and an axially shifttable spring-pressed sealing, locking and press-button part assembled with said socket and presented at said aperture.

9. A separable fastener comprising, in combination, a stud assembly having a contractible and expandible head and means providing an opening entirely through the stud assembly, a cooperating socket presenting a stud-receiving aperture, a locking part forming part of the fastener assembly for locking said stud and socket against accidental separation and a press button carried by the socket, said press-button adapted to pass through the opening in the stud assembly to be operable from the outer face of

said stud to shift said locking part and permit separation of the fastener.

10. A separable fastener comprising, in combination, a socket comprising a casing secured to a suitable support and presenting a stud-receiving aperture, a combined press-button, locking and sealing part carried by said casing and a spring normally urging said part toward said aperture, a cooperating stud carried by a flexible carrying medium and presenting a part to be locked in said aperture by the locking portion of said part and a passage through said stud into which the press-button portion of said part may pass to permit operation thereof from the outside face of said stud.

In testimony whereof, I have signed my name to this specification.

FRED S. CARR.
